UNITED STATES PATENT OFFICE.

CORA CAVNER, OF ARDMORE, OKLAHOMA.

INCUBATOR.

Application filed January 8, 1926. Serial No. 80,038.

This invention relates to improvements in incubators, and has for an object to provide a compact device for hatching the eggs.

Further objects of the invention lie in so 5 coordinating and arranging the various parts as to enable the apparatus to be operated with an economy of fuel; and to distribute the heat uniformly throughout the entire hatching chamber as required to secure the best results.

With the foregoing and other objects in view, the invention will be more fully described hereinafter, and will be more particularly pointed out in the claims appended 10 hereto.

In the drawings, wherein like symbols refer to like or corresponding parts throughout the several views,

Figure 1 is a plan view, with parts broken 20 away, of the complete device constructed according to the present invention,

Figure 2 is a front elevation also with parts broken away, of the complete device,

Figure 3 is a vertical section taken on the 25 line 3-3 in Figure 1,

Figure 4 is a horizontal section taken on line 4-4 in Figure 2,

Figure 5 is a perspective view of the device converted as a brooder,

Figure 6 is also a perspective view of the 30 cover for the incubator casing,

Figure 7 shows a perspective view of the incubator egg tray, and

Figure 8 is also a perspective view of the 35 incubator shell or casing.

Referring more particularly to the drawings, 9 designates generally an external hood enveloping the incubator casing or shell 10 and its cover 11. The external cylindrical 40 wall of the hood may be made of sheet metal or other appropriate material. The top portion or roof 12 of the hood is of conical form in order to regulate and distribute the heat more uniformly, and near the apex of the cone roof are a number of openings 13 restricted in diameter to permit the escape of smoke and the gas fumes. These fumes encounter a horizontal deflecting plate 14 situated above the apex of the cone and supported thereon as by the feet 15. The deflecting plate 14 is formed with the down-turned saucer-like rim 16 to deflect the heated products of combustion in substantially parallel streams along the conical roof 45 of the hood. The hood both as to its cylindrical wall 9 and cone roof 12 is lined with

an appropriate heat-insulating material represented at 17 and 18 and this lining material is preferably placed externally of the hood and may be secured thereto in any appropriate manner.

The hood, when in use for the incubating operation, is supported upon elongated legs, each of which is preferably formed of a single strand of wire, the intermediate portion 19 of which is rounded to form a foot for contacting with the ground or supporting surface. The wire diverges upwardly from the rounded portion 19 providing the two supporting members 20 and 21, at the 50 upper ends of which the wire is turned laterally to provide the two supporting shoulders 22 and 23 adjoining the upturned extremities 24 and 25 used for the purpose of anchoring the legs to the cylindrical portion of the 55 hood. The inner wall of the cylindrical hood portion 9 is provided with metallic or other straps 26 having the pairs of sockets or casings 27 and 28 to receive the anchoring 60 extremities 24 and 25 of the legs. These 65 extremities simply slip into the sockets 27 and 28 and the lower rim of the cylindrical wall 9 of the hood is received upon the shoulders 22 and 23, thus serving to support the 70 hood and also to lock the legs in place. It is 75 also preferred that the wire of which the legs are made shall possess a certain inherent 80 resiliency and that the legs will be so made that this resiliency will tend to spread the 85 supporting members 20 and 21 slightly 90 apart, making it necessary to squeeze these 95 members slightly in the hand in order to bring the members 24 and 25 into correct 100 alignment before inserting them in the 105 sockets 27 and 28. As a consequence, the 110 tendency of the members 20 and 21 to separate because of this inherent resiliency will create a considerable degree of frictional contact between the walls of the sockets 27 and 28 and a large surface area presented by the extremities 24 and 25, so that the hood may be lifted up without resulting in the falling out or detachment of the legs. These legs may be provided in any suitable number; three such legs are shown by way of example and it might be said that three legs have been found ample in practice.

The casing or shell 10 which houses the incubating chamber is clearly shown in Figure 8 and it is also constructed with an outer cylindrical wall conforming to the cylindrical wall of the hood, although being of

considerably less diameter to provide an annular space between the incubating casing and hood for the circulation of the heated air developed by the lamp 29 shown in Figure 3.

Reverting to the casing 10, it is to be understood that the casing may be made up in other shapes than the cylindrical shape shown, as may also the hood 9, but the cylindrical shape will probably be most compact. The casing or shell 10 is also preferably made from sheet metal with a bottom portion 30 and an upstanding column 31 providing an internal flue 32 into which 5 projects the chimney of the lamp 29 or other heating device. The column 31 is open at its upper end and it is preferably disposed slightly below the rim of the outer wall 10 and appropriate packing or insulating material is placed within the walls 10, 30, and 31. The rim of the wall 10 is provided with the out-turned flange 33 at the outer end of which is provided an upturned flange 34, forming a right angle structure which reinforces the upper edge of the incubating casing or shell and which also has the further function of co-operating with the out-turned flange 35 on the lower external rim of the cover portion 11. This cover portion is provided with the vertical cylindrical wall 36; with a flat horizontal roof portion 11, and with the hollow tube 37 depending from the inner portion of the roof 11 and opening at its upper end through the roof. This tube 37 is small in diameter as compared with the diameter of the hollow column 31 and it fits into hollow column 31 and downwardly over the chimney of the lamp. The various members of the cover are also preferably lined interiorly as shown. An annular space 38 is provided between the column 31 and tube 37 and this space is open at both its upper and lower ends.

In the incubating chamber inclosed by this casing and its cover is placed the tray 39 which may also be of sheet metal and which preferably contains the felt or other pad 40 for directly receiving the eggs to be hatched. These eggs are confined in the tray by the outer shallow flange 41 and by the internal circular fall 42 of greater height than the flange and fitting about the lining 43 of the column 31. The engagement of the wall 42 with a lining 43 will provide for the centering of the tray and for its rigid support in the incubating chamber; but due to the interposition of the compressible lining 43 between the walls 31 and 42, the tray may be placed and removed without difficulty.

Moreover, the presence of the lining spaces the metal apart, which would otherwise exhibit a too great conductivity.

The tray is supported in the incubating chamber by the legs 44 made similar to the legs previously described for the hood, ex-

cept that the terminal portions 45 and 46 of the legs 44 are bent substantially horizontally to fit in the casings provided by the horizontal plates 47 on the bottom 39 of the tray. These legs may be withdrawn in an outward radial direction when desired. The outer flange 41 of the tray is spaced a considerable distance from the wall 10 or its lining 48. There results from this construction a space for the escape of the newly hatched chicks and this escape is rendered the more easy by the comparatively low flange 41. The hatched chicks may thus spread into the bottom of the hatching chamber.

The entire casing 10 and its cover 11 are supported upon legs 49 similar to the legs 44 and mounted in casings upon the straps 50 secured to the bottom 30 of the casing. The legs for the hood and casing are preferably so arranged as to support the bottom 30 of the incubating chamber slightly above the lower edge of the hood 9 throughout the normal incubating procedure.

As shown in Figure 8, the side wall 10 of the casing or shell is accessible through a door 51 hinged as indicated at 52 and provided with a hasp or other locking arrangement indicated generally at 53. Moreover, the casing is provided with a sight opening 54 in its side wall to permit inspection of the action within, and this inspection is aided by the lamp 55 also mounted through the wall 10 of the casing and being controlled externally as by the switch 56.

Any suitable moistening means may be employed for imparting the desired degree of humidity to the incubating atmosphere.

In the operation of the device, eggs are placed upon the tray shown in Figure 7 in suitable number and the tray is placed in the casing or shell indicated in Figure 8 after which the cover shown in Figure 6 is fitted over the casing. The hood shown in Figure 5 is thereafter placed over the incubating chamber thus assembled and we have the device illustrated in Figure 3. The lamp or other heating device is lighted, and the action of incubation begun. The heat from the lamp will ascend up through the tube 37, the smoke and fumes passing out through the openings 13 in the conical top 12 of the hood. Fresh air in a heated condition will be drawn up by the convection currents to and through the annular passage 38 and to the eggs in the tray, which eggs are kept from rolling around due to the contact of the eggs themselves and the engagement of the outermost eggs with the corrugated rim 41 of the egg tray. The conical dome or roof 12 of the hood is of advantage over a flat roof in causing a more even distribution of the heat to all parts of the atmosphere circumscribed within the hood. This atmosphere envelops the walls

of the incubating chamber and it is desirable to maintain said atmosphere as uniform in temperature as practicable. The heat will ascend promptly to the uppermost or apex portion of the roof or dome and as it accumulates here, it will be deflected downwardly or outwardly to the space between the incubating casing and the hood. It will also be deflected along the top 11 of the cover portion due to the fact that the space above the incubating chamber decreases in cross-section from the central portion above the cover to the outer part where this space communicates with the annular space between the side walls 9 and 10. There will therefore be a congestion near the angle portions of the walls 9, 12 and 10, 11, which will cause the heat to flow radially and inwardly along the top of the cover 11. It is important that the air-passage 38 be present and the co-operation of the flange parts 33, 34, and 35, secures the proper spacing of the tube 37 and the column 31 without any particular attention on the part of the assembler.

As the eggs are hatched, the young chicks or some of them, may get over the corrugated rim 41 into the bottom of the incubating chamber where there will be greater freedom of movement. The action may be observed from time to time through the sight opening 54, and the lamp 55 lighted each time by closing the switch 56. As the chicks accumulate, they may be removed through the door 51.

It will be appreciated that the device, owing to the even distribution of heat and to the arrangement of the central passage 38, may be operated at considerable economy of oil or other fuel; and that the process of hatching may be carried out more expeditiously. The entire apparatus may also be constructed at a very small initial cost.

It is obvious that various changes and modifications may be made in the details of construction and design of the above specifically described embodiment of this invention without departing from the spirit thereof, such changes and modifications being restricted only by the scope of the following claims.

What is claimed is:—

1. An improved incubator comprising an enveloping hood, an incubating casing supported within the hood and provided at its upper wall with out-turned flanges, and at its inner portion with an upstanding hollow column, a cover for said casing having at its outer part an out-turned flange seated upon and centered by the first-named flanges of the casing, and having at its central portion a depending tube entering said hollow column and spaced therefrom to provide a passage for the circulation of air to the interior of the incubating chamber, and heating means disposed below the said tube and column.

2. An improved incubator comprising an enveloping hood, an incubating casing supported therein and having a central hollow externally lined column, a cover for the casing having a tube spaced from and extending into said column, heating means below the tube, and a tray for the eggs supported in said casing and having an inner wall adapted to envelop and engage with the padding on said hollow column.

3. An improved incubator comprising an enveloping hood, an incubating casing supported therein having a central hollow column, a cover on the casing having a central tube extending into the column and spaced therefrom, heating means below the tube, an egg tray having a corrugated shallow outer wall and a relatively deep inner wall engaging about said hollow column, and legs to support the tray at an elevation above the bottom of the incubator case.

4. An improved incubator comprising an enveloping hood, an incubating casing supported therein having a central hollow column, a cover on the casing having a central tube extending into the column and spaced therefrom, heating means below the tube, an annular tray having a bottom portion, a shallow outer corrugated wall spaced from the adjacent wall of the incubating chamber and an inner deeper wall surrounding said hollow column, a pad on the base portion of the tray, and legs to support the tray above the bottom of the casing.

Mrs. CORA CAVNER.
